WARDROBE HOOK

La Verne E. Clayton, Rockford, Ill., assignor to Amerock Corporation, Rockford, Ill., a corporation of Illinois

Filed Nov. 2, 1961, Ser. No. 67,365

Term of patent 14 years

(Cl. D17—12)

FIG. 2 is a top view.

FIG. 3 is a front view of the wardrobe hook.

FIG. 4 is a side view.

The design is particularly characterized by the proportions of the three hooks relative to the base and by the gradual widening of the hooks toward their ends.

I claim:

The ornamental design for a wardrobe hook, substantially as shown.
